UNITED STATES PATENT OFFICE

2,005,452

INDICATING DEVICE

William F. Bull, Brooklyn, N. Y.

Application November 1, 1930, Serial No. 492,772

3 Claims. (Cl. 199—30)

My invention relates to indicating devices and refers particularly to composing and typesetting machines, charts, scales and similar devices to which it can be applied.

5 The prime objects of the present invention are to provide an inexpensive, simple, durable, positive, easily applied and efficient device for the purpose herein described; for describing and illustrating the present invention I have shown same 10 as applied to a typesetting machine.

As an illustration, in composing what is generally known as "tabular" matter, it is necessary to arrange figures or characters in the different lines in the same vertical line or columnwise 15 alignment; it is also necessary to predetermine the desired spacing of the groups in the dividing of the line into the desired number of groups, in general to predetermine the location of figures and characters in linewise direction. I have 20 shown the present invention applied to a composing machine to determine the above said vertical or columnwise alignment of figures or characters and to secure the desired spacing of the groups in linewise direction.

25 The present invention may also be used to advantage in composing irregular matter, arranging figures and characters to present a geometrical figure, such as a triangle or other figure and for indentations, leaders, "runarounds", type arranged 30 to conform to the shape and size of an illustration, for progressively increasing or decreasing the length of succeeding lines.

On the drawing Fig. 1 is a view of the present invention in one form as viewed from the operator's position. Fig. 2 is a side elevation of 35 Fig. 1. Fig. 3 is a detail view of one type of indicating marker. Fig. 4 is a plan view of one end of the device and shows more particularly the means of supporting and attaching the present invention to the machine. Fig. 5 is a side view of Fig. 3. Fig. 6 shows a modified type of indicating marker which is also shown at 11 in Fig. 1. Fig. 7 40 shows another type of indicating marker.

45 As hereinbefore described, the present invention is illustrated on the drawing as applied to a composing machine and as shown is attached to the composing machine by a suitable bracket 1 held by a screw 2 which enters a structural member 3 of the machine, the said bracket 1 has an 50 extension 1a which has a U-shaped slot 1b for receiving a suitable bar 4, said bar 4 is retained in the bracket 1 at the bottom of the said U-shaped slot 1b by a suitable screw 5, the said screw 5 is located in the bracket 1 in a manner to push the bar 4 into the bottom of the slot 1b.

Said bar 4 may be of any suitable cross-section such as round, square, rectangular, oval, fluted, etc.

5 As shown on the drawing and herein described, the present invention is applied to a keyboard of a type of composing machine commonly known as the "Monotype" composing machine keyboard. The "em" scale 6 is stationary; the em rack pointer 7 is carried on the em rack 7a and moves forward as the line is composed and thus indicates 10 what portion of the line has been set or composed. Indicators of the type shown at 10 in Figs. 1, 2, 3 and 5 are made from two pieces of flat spring material having the narrow ends firmly joined together as shown in Fig. 3 and in their 15 free position have an opened shape which is also shown in Fig. 3. In putting the said indicators on the bar 4 the separated or spread apart ends are pressed together and the bar 4 inserted through the hole 10a and as the ends 10b are released the indicator will tend to assume its free shape and thus clamp itself onto the bar 4; by pressing together the lower end 10b the indicator 20 may be moved to any lengthwise position on the 25 said bar 4 or rotated thereon as indicated at 10c in Fig. 2 as when it is desired to make an intermediate indicator inoperative, or when it is desired to make all indicators inoperative the bar 4 with all indicators remaining in their set position 30 is rotated to bring the said indicators into the position shown at 10c in Fig. 2. The movable markers may in some cases be constructed as 35 shown in Fig. 7 which differs from that shown at 10 in Figs. 1, 2, 3 and 5, by having the hole extended to the edge to permit removing the individual marker from the bar 4. Any number of 40 indicators may be used on the bar 4, the number of course corresponding to the class of work usually performed on the machine. The said bar 4 is axially located by suitable collars 8 secured to the bar 4 by suitable means such as screws 9, the bar 4, with the collars 8 and indicators 10 remaining in their set position may be removed 45 from the machine by the unscrewing of the bar retaining screws 5 and a different bar having other spacings of the indicators substituted, without disturbing the "set-up" on the bar being removed or put on the machine. On certain classes of work it may be desirable to make use of more 50 than one series of indicators, in which case it would be more convenient to use a number of bars (4) each with a desired indicator setting as the said bars 4 are quickly removed from and replaced on the machine with the indicators and bar properly located by the collars 8 as above de-

scribed. When jobs occur at intervals or when lines have a different spacing the bar 4 may be removed from the machine and stored until again required.

5 Having thus described my invention what I claim as new and desire to secure by Letters Patent is:

1. In an indicating device, in combination, indicia, a bar in proximity to said indicia, tension held indicators or markers movable on said bar lengthwise of said indicia, said indicators or markers movable on the bar to and from operating position with said indicia.

10 2. In an indicating device, in combination, a scale, a bar in proximity to said scale, automatically held indicators or markers movable on said bar along said scale and movable to and from operative relationship with said scale, said indicators having common means of support, said

20 support removable from machine with indicators

in set position, removable and interchangeable indicator supports, said support provided with means of location relative to said scale, slotted means on the machine for receiving said indicator support, and means to fix said indicator support in said slotted receiving means.

3. In an indicating device, in combination, indicia, an indicator supporting bar in proximity to said indicia, tension held indicators or markers on said bar movable with respect to indicia and movable to and from operation with said indicia, said indicators having common means of support, said support removable from machine with indicators or markers in set position for purpose hereinbefore outlined, said support provided with means of location with respect to said indicia, slotted means on the machine to receive said indicator support, and means to fix said indicator support in said slotted receiving means.

WILLIAM F. BULL. 20
